UNITED STATES PATENT OFFICE.

WILLIAM C. CUTLER, OF NORTH GLENDALE, CALIFORNIA.

INFORMATION STORING AND DISPLAYING DEVICE.

1,385,116.

Specification of Letters Patent. Patented July 19, 1921.

Application filed March 16, 1921. Serial No. 452,698.

To all whom it may concern:

Be it known that I, WILLIAM C. CUTLER, a citizen of the United States, residing at North Glendale, in the county of Los Angeles and State of California, have invented a new and useful Information Storing and Displaying Device, of which the following is a specification.

This invention relates to devices for storing information, and for displaying chosen matter of the stored information when operated.

One of the objects of this invention is to provide a device so designed that it will not likely get out of working order.

Another object is to provide a device of this type with positive actions and movements and still maintaining a suitable flexibility.

Another object is to provide a spring and ratchet-like brake for the setting mechanism, designed and arranged so as to cause a slowing down of the movement of the setting mechanism as soon as the foot pedal is touched and completely locking the setting mechanism when the foot pedal is in its lowermost position.

Another object is to provide a movable curtain in rear of the position in which the information matter is normally displayed.

Another object is to provide notches in the card-carrying members of the device of a shape and size to retain the cards easily and securely even when the carrying members are moved to a position to bring the notches to project in a practically sidewise direction.

Another object is to provide power storing means in the shaft of the card lifting mechanism to remain locked and tending to increase power up to the time when the foot pedal reaches its lowermost position.

Another object is to provide a spring fan for retarding the movement of the card lifting mechanism.

Another object is to provide cushioning, supporting, and guiding means for the card lifting hooks to occupy little space, to require little accuracy in the manufacture and in assembling the device, and still provide proper accuracy and satisfactory service when applied.

Other objects will appear from the following description and appended claims as well

as from the accompanying drawing, in which—

Figure 1 is a general vertical cross sectional view of the device, fully assembled, having practically only one end plate of the cabinet removed and therefore nearly representing an end or a side elevation of the device.

Fig. 2 is a fragmentary detail front elevation of the card-lifting hooks with weights and guiding members.

Fig. 3 is a fragmentary detail front elevation of the card-lifting mechanism.

Fig. 4 is a fragmentary detail side elevation of the foot pedal terminating within the front wall or member of the cabinet of the device, as a slight modification of the arrangement in Fig. 1.

Fig. 5 is a top plan view of the slightly modified arrangement of the foot pedal and cabinet in Fig. 4.

Fig. 6 is a fragmentary detail front elevation of the shaft with the several pulleys for the card lifting tapes, illustrating the adjustability of the one pulley in relation to the other pulleys on the same shaft.

Fig. 7 is a side elevation of a turnbuckle in combination with the attaching end for the tapes in detail.

Fig. 8 is a cross section of the lifting hook on line 8—8 of Fig. 9.

Fig. 9 is a detail front elevation of one of the lifting hooks.

Fig. 10 is a top plan view of the hook in Fig. 9.

Fig. 11 is a fragmentary detail side elevation of the braking mechanism of the setting mechanism.

Fig. 12 is a front elevation of the outside of the device with the upper part of the glassed in opening and wall and the lower part of the wall, taken away, showing the indicating means in operative relation to the index means.

It is customary to place this kind of devices in public places and at points where they can be reached at any time and by anyone desiring to use them. Any working mechanism can however easily be thrown out of working order when so placed at points not under the control or supervision of experts or persons experienced with the devices. To avoid such happenings with a device of this type, it is the main object in

view to provide suitable details and parts that will and cannot likely be tampered with from the outside to such an extent that the principal inner working mechanisms are materially influenced even if the outer terminations or members of the mechanisms are touched.

The cabinet 12 incloses the principal working mechanisms above referred to. 10 The hand lever or handle 13 forms the outer termination or outer member of the setting mechanism of the device. The foot pedal 14 forms the outer termination or outer member of the lifting mechanism. The setting and lifting mechanisms form the principal combinations of parts arranged in this device.

The storing members 15 are provided for movably supporting the cards 16. The cards 20 are suspended on the pins or bars 17, provided on and along one edge of the cards so as to project over the side edges, as clearly illustrated in Fig. 2. In storing position, the ends of the pins of the cards rest in the 25 notches 18 of the storing or card supporting members 15 in a position to swing freely over the hooks 19 of the card lifting members.

The card lifting hooks are illustrated in 30 detail in Figs. 8, 9 and 10. The hooks 19 are provided with recesses 20 to receive and hold the pins of the cards. These recesses are designed of larger dimensions in the lower portions 20 than in the upper receiving 35 portions, as indicated at 21 in Fig. 8. A card descending into storing position, and also when lifted out of storing position cannot easily be shaken out of such recesses in the hooks.

40 The notches 18 in the storing and card-supporting members 15 are similarly shaped, being of larger dimensions in innermost portions as indicated at 22 and of narrower size near the receiving edges as indicated 45 at 23.

A card, replaced by the lifting hooks 19 into the notches 18 of the storing members 15, descends easily through the narrow opening at 23 into the larger holding recess 22. 50 The cards hang in their storing and inoperative position between the two storing and supporting members 15 in the notches in the edges of the storing members 15. The hooks 19 are in their resting and inoperative position below the ends of the pins 17, as clearly 55 illustrated in Fig. 2.

The card storing and supporting members 15 are swingably mounted on the pins 24 on the sides of the cabinet, so that the cards 60 can hang and freely swing between the two members 15.

The notches 18 are provided and arranged as close as possible one to the other so that the possibly largest number of cards 16 can 65 be stored on the members 15. In the draw-

ing, the notches may appear rather large in proportion to the thickness of the cards, but if will easily be understood that such proportioning and arrangement is only made to make the illustration as clear as possible, 70 and that the cards may be stored much closer than illustrated, and in fact always are stored as close as possible, as long as a selected card may easily be removed from its storing position to view position and back 75 without disturbing the next cards.

The selective position from which the selected card is lifted into view position is indicated at 25. Any of the stored cards on the storing and supporting members 15 80 must be moved to selective position to be lifted into view position. All the stored cards are therefore kept in proper order, and an index is placed and kept in a suitable position on or in the device by which any of 85 the stored cards may be located. The index marks are corresponding to marks on the front glass, indicated at 26. An indicating member 27 is movable behind the glass 26. Gears or other similar suitable members 28 90 are inserted between the storing members 15 and the indicating member 27, so that the positions of the several cards on the storing members correspond to the marks on the front glass and thereby to the index. 95

The hand lever or handle 13 serves to move and swing the storing members 15 and thereby the stored cards to selective position. A drum 29 is provided on a common shaft 30 with the handle 13. A flexible 100 member 31 is wound a suitable number of times around the drum to properly engage the drum and passes also over the pulley 32 to which the ends of 31 are attached to properly engage the pulley. The small pulley 33 serves to guide and properly hold the flexible member 31 to the drum and pulley 32. A connecting rod 34 is pivotally engaging with the pulley 32 at 35 and also pivotally engaging with the pulley 36 at 110 37. Since the pulley 32 is smaller than the pulley 36, the pulley 36 swings or practically oscillates only to a short extent while the pulley 32 is apt to make full turns. The pulley 36 is provided on both ends of the 115 shaft 38, so that the two pulleys 36 transmit their oscillating movement to the pulleys 39 by the flexible members 40. The pulleys 39 are provided one on each of the storing members 15.

Making the drum 29 proportionally small compared to the several pulleys, allows a rather quick movement of the handle 13 without materially disturbing the slower moving other parts with the cards. 120

The spring 41 is provided for balancing the storing members 15, so that the setting mechanism may be operated just as easily when the cards are all hanging toward one side of the central support, that is when the 130

last or one of the last cards of the whole number of stored cards on either end is in selective position, in Fig. 1 the cards being shown practically centralized with the centralmost card in selective position. The spring 41 stretches when the storing members 15 are moved away from this central position in either direction.

The lifting hooks 19 are provided with 10 weight members 42 and connecting rods 43. Flexible members 44 are provided to connect the lifting hooks to the pulleys 45. Two pulleys 45 are provided on a common shaft 46, so as to assure an even and equal 15 movement to both oppositely arranged lifting hooks, see Figs. 1, 2 and 6. A third pulley 47 is provided to connect the flexible member 48 of the lifting means. The flexible member 48 connects the pulley 47 with 20 the rod 49, as indicated at 50. The second end of the connecting rod 49 is pivotally connected to the disk 52, as indicated at 51.

A turning of the disk 52 produces a downward movement of the rod 49 with the flexible member 48, and thereby a turning of 25 the shaft 46. Turning the shaft 46 causes a winding of the flexible members 44 on to the pulleys 45, and thereby a lifting of the lifting hooks 19.

For correcting the lifting position of the 30 lifting hooks in relation to the flexible member 48, the pulley 47 is adjustably engaged with the shaft 46, as by a set screw as indicated at 53 in Fig. 6.

In their vertical movement, the lifting 35 hooks 19 are guided by the rods 54 as illustrated in Fig. 2. The hooks 19 are for this purpose provided with the eyes 55 to slidably engage with the rods 54, see also Figs.

9 and 10. The lower terminations of the 40 rods 54 are preferably shaped in loop form, as indicated at 56 to project below the hooks for supporting the hooks in their lowermost positions. To avoid a clicking or any

similar noise or any hard jar when the hooks 45 descend into resting positions, the cushions 57, made of rubber or any other soft resilient material, are provided or disposed on the looped portions of the rods 54.

The disk 52 is actuated by the foot pedal 40. The motion of the foot pedal in its downward movement is transmitted through the connecting rod 58 to the lever 59. The lever 59 is pivotally mounted at one end as

55 indicated at 60 and with its free end 61 touching the edge 62 of the lever 63. The lever 63 is mounted on the shaft 64, which may be of solid material or tube-like. The shaft 64 is turnably disposed in the tube or

60 sleeve portion 65 of the shaft, as indicated at 66. The sleeve portion 66 and the smaller shaft 64, fitting in the sleeve portion 65, normally form one shaft interconnected by the spring 67, one end of the shaft being 65 turnably mounted in the box 68 and the

other end in the box 69. One end of the spring is engaged with the hub of the pulley 72 as indicated at 70, while the other end of the spring is engaged to the lever 63 as indicated at 71. The pulley 72 and disk 70 52 are mounted on the sleeve portion 65 of the shaft, while the lever 63 is mounted on the portion 64 of the shaft.

A moving of the lever 63 produces a straining of the spring 67 to such an extent as to store power for moving the pulley 72 and disk 52 at a desired moment, as will be described later on.

The arrangement of the foot pedal 14, the connecting rod 58, the lever 59, and the lever 63, as illustrated in Figs. 1 and 3, is made to provide for a movement of the foot pedal downwardly and thereby locking the levers 59 and 63 until the foot pedal is back to near its normal uppermost position when the foot pedal becomes locked until the other levers are back to their normal inoperative position. The operation of the foot pedal transmits motion to lever 59 through connecting rod 58, the lever 63 tending to store power in the spring 67 and being affected by the tension of that spring, therefore causing a snapping back of the lever 63 as soon as the lever 59 with its end 61 passes beyond the point 73 of the lever 63 so that the end 61 of the lever 59 engages under the end 73 of the lever 63 as indicated in dotted lines at 74. As soon as the foot pedal is released, it snaps back to its uppermost position by the action of the spring 75. On reaching the uppermost position, the hook end 76 of the foot pedal engages below the hook end 77 of the lever 63, thereby pushing or moving the lever 63 to release the end 61 of the lever 59 from engagement with the lever 63.

The lever 59 moves back to inoperative position by the action of the spring 78. The lever 63 is then free to move back to inoperative position, the hook end 76 of the foot pedal 14 being in a position above the arch-shaped lip or bead 79 on the lever 63, so as to prevent a downward movement of the foot pedal until the lever 63 has reached its normal inoperative position, the point 80 of the lever 63 being in such inoperative position past the hook end 76 of the foot pedal as illustrated in Figs. 1 and 3.

A flexible member 81 connects the pulley 72 with the pulley 82 on the shaft 83, the pulley 82 being much smaller than the pulley 72, so as to cause the shaft 83 to rotate proportionally fast when the pulley 72 is rotated slowly by the action of the spring 67. The spring fan wheel 84 serves as a 125 governor for the movement of the pulley 72. The spiral spring 85 is wound by the action of the shaft 83 described above, since the end 86 of the spiral spring is secured to the cabinet, storing power for returning the 130

shaft 83 and thereby the pulley 72 and disk 52 with the lever 63 to normal inoperative position.

The disk 52 is prevented from moving by the lever 88, a perforation 87 being provided in the disk 52 to engage with the lever 88. On reaching its lowermost position, the foot pedal 14 presses on the lever 89 thereby moving the lever 89 and thereby the rod 90 and the lever 88. The disk 52 is in this manner only released for movement when the foot pedal reaches its lowermost position. The levers 88 and 89 are brought back for engaging with the disk by the spring 91. The desired moment to operate the disk 52 and pulley 72, referred to above, is when the foot pedal is in its lowermost position, having the lever 59 engaged with the lever 63 so that the spring 67 is subjected to its highest tension.

When the disk 52 is released from engagement of the lever 88, the disk 52 is rotated under the tension of the spring 67, controlled by the spring fan 84, thereby producing a slow downward movement of the rod 49 with the flexible member 48, resulting in a lifting of the hooks 19 with the selected card from the selective position at 25.

As soon as the foot pedal is released, the hook end 76 of the foot pedal moves the lever 63 to free the end 61 of the lever 59 thereby freeing also the lever 63, since the hook end 76 of the foot pedal reaches at such a moment a point above the lip 79 of the lever 63, thereby locking the foot pedal against downward movement until the lever 63 reaches its normal inoperative position with the point 80 of the lever 63 past the hook end 76 of the foot pedal 14.

As soon as the lever 63 is released, the stored power in the spring 85 serves to return the lever 63 and therewith the pulley 72, the disk 52, the rod 49, the flexible members 48 and 44, and the lifted card to normal inoperative position.

The front end of the foot pedal is preferably within a recessed portion 92 in the front plate of the cabinet 12, so as not to protrude out of the front wall of the cabinet, even though illustrated in Fig. 1 as projecting out of the cabinet, this illustration being only made since the Fig. 1 is rather crowded and would eventually not be so clear if more details had been shown.

See detail illustrations in Figs. 4 and 5.

A connecting rod 93 connects the foot pedal 14 with the spring brake member 94, as illustrated in detail in Figs. 11 and 1, in Fig. 1 it being only indicated in dotted lines connected behind the pulley 32. The spring brake member 94 serves to engage with the ratchet or toothed wheel 95. The teeth and spring member are illustrated of rather coarse design, but it will easily be understood that the teeth of the wheel 95 must

align or correspond to the number of notches 18 in the card carrier 15, so as to align the card carrier properly when the brake member is operated by the foot pedal to bring one of the stored cards properly into selective position.

On the upper end of the lifting rod 49, the rod-end 50 is preferably formed in an open split end 96. The lifting tape or flexible member 48 is folded upon itself as indicated at 97, and a pin 98 is inserted between the folds so as to firmly engage the flexible member 48 within the end of the rod 49. The pin 98 can, of course, be made taper to easily slip in between the folds of the flexible member within the split end 96 when the pin is first inserted to gradually become tight and secure within the split member on being pushed in further, as will easily be understood, but it is not absolutely necessary, since the split end easily gives enough to allow a pin to slip in even if the pin and the material of the flexible member first seem to be too large. A turnbuckle 99 is preferably inserted as illustrated in Fig. 7.

A movable endless curtain 100 is disposed within the cabinet 12 in a position so that a portion of the curtain can be seen behind the glass front when the information displaying cards are in storing position. The curtain is for advertising matter to be shown portion after portion automatically by the movement of the lifting mechanism of the device, and is for this purpose provided with pins 101 or any other similar means to engage with hooks 103 or any other similar suitable means on the flexible or lifting member of the device. The curtain 100 is disposed over rollers 102 as indicated in the illustration in Fig. 1. In the downward movement of the flexible member 48, the hook 103 engages with one of the members 101 on the curtain and thereby moves the curtain to bring other portions of the curtain into view position. As soon as the selected card, lifted by the lifting mechanism by such an operation, has again reached its storing position away from the view position, the new advertising matter on the curtain is in view position.

The illustration in Fig. 12 is a slightly modified form of indicator easily within the scope of the invention, the rack bar 104 engaging with a gear 105 and thereby moving the indicator 106 on the band 107 in a horizontal line past the marks 108 on the front glass of the cabinet 12.

Having thus described my invention, I claim:

1. In a device of the class described, a series of cards, a pair of circular card carrying members having pocket like notches in their outer edges to retain the cards at a lower than horizontal position of the notches, said cards having means to engage

- in the notches of the card carrying members, a foot lever, a rotary hand lever having means operative to bring any of the cards into selective position, means operative by 5 the foot lever to lift the selected card from the circular card carrying members into view position, and means for retarding the action of said foot lever and restoring the same to its starting position.
- 10 2. In a device of the class described, a series of cards, a pair of circular card carrying members having pocket-like notches in the outer edges to retain the cards at a lower than horizontal position of the 15 notches, said cards having means to engage in the notches of the card carrying members, a foot lever, a rotary hand lever having means operative to bring any of the cards into selective position, lifting hooks having 20 a narrower upper receiving portion and a lower wider holding portion for securely holding the card when lifted from the carrying member into view position, means connecting the foot lever and the hooks, guiding 25 rods for the lifting hooks, and means on the hooks for slidingly engaging with the rods.
3. In a device of the class described, a series of cards, a pair of circular card carrying members having pocket-like notches in the outer edges to retain the cards at a lower than horizontal position of the 30 notches, said cards having means to engage in the notches of the card carrying members, a foot pedal, means operated by the 35 pedal for moving one card away from the other cards in the card carrying members into view position, means for returning the 40 moved card back to storing position in the card carrying members, means connecting said handle to said card carrying members, and means for braking and finally locking said handle by the movement of the 45 foot pedal.
4. In a device of the class described, card carrying members having each a driving and setting pulley, two other pulleys mounted on a common shaft below the first-named 50 pulleys of the card carrying members, belts connecting the upper and lower pulleys, a rotary handle, means connecting said rotary handle with the shaft and lower pulleys to produce an oscillating movement of the card 55 carrying members having the several pulleys arranged and proportioned so as to give such a result, a series of cards on the card carriers, and means for moving one of the cards on the carriers into view position and 60 back.
5. In a device of the class described, a series of cards, a rotary hand lever, a foot lever, means operative by the rotation of the hand lever to move any one of the cards to 65 selective position, means operated by the foot lever to move the selected card out of selective position into view position, a rotary spring motor, and means operated by the spring motor to retard the moving of and restore the operating parts of the device to 70 inoperative position.
6. In a device of the class described, upper circular card carrying members containing card carrying means, cards, a rotary hand lever, lower circular members, connecting means between the lower circular members and the rotary hand lever, belts connecting the upper and lower circular members, means operative by the hand lever to produce an oscillating movement on the upper circular and card carrying members, 75 means for retaining said cards in the card carrying members when moved below the horizontal center line of the carrying members, and means for lifting a desired card 80 from the carrying members into view position.
7. In a device of the class described, a series of cards, a pair of circular card carrying members having pocket-like notches in 85 their outer edges to retain the cards at a lower than a horizontal position of the notches, said cards having means to engage in the notches of the card carrying members, a foot pedal, means operated by the 90 foot pedal for moving one card away from the other cards in the card carrying members into view position, a recess in the lower front of said device and means for terminating said foot pedal within said recess. 95
8. In a device of the class described, a cabinet having a glassed in opening in a portion of its front, a pair of circular card carrying members having pocket-like notches in their outer edges to retain the 100 cards when moved to a lower than a horizontal position of the notches, index means under the glass across the lower portion of the glassed in opening, a rotary handle, means connecting the rotary handle to the 105 card carrying means so as to move any one of the cards to selective position and indicating means operative to register with said index means. 110
9. In an information storing and displaying device, in combination with card storing and displaying mechanism, a movable endless curtain containing advertising matter of which a portion is normally in view position having means operative by the said 115 storing and displaying mechanism when moved between storing and displaying position to change the advertising matter in view by moving the endless curtain. 120
10. In an information storing and displaying device, in combination with the lifting tape, a split end member having a practically cylindrical cross hole so that the end of the lifting tape may be folded upon itself and secured within the split end member by 125 130

an inserted round pin within the fold of the tape.

11. In an information storing and displaying device, in combination with the shaft and pulleys on the shaft by which the card lifting tape is operated, a setting and adjusting means between one of the pulleys and the shaft for adjusting the lifting position and mechanism.
- 10 12. In an information storing and displaying device, in combination with the lifting hooks, an upright bar disposed near both ends of the lifting hooks for guiding the lifting hooks, the lifting hooks having eye-shaped members for slidably engaging with the bars.
13. In an information storing and displaying device, in combination with the card selecting mechanism and the card lifting

mechanism, a foot lever connected with the card lifting mechanism, means for locking the lifting mechanism when the foot lever reaches its lowermost position, and means on the foot lever for unlocking the lifting mechanism when the foot lever reaches its uppermost position adapted to lock the foot lever with the lifting mechanism in such uppermost position of the foot pedal until the lifting mechanism has reached its normal inoperative position.

In testimony that I claim the foregoing as my invention I have signed my name in the presence of two subscribing witnesses.

WILLIAM C. CUTLER.
